12 Claims

ABSTRACT OF THE DISCLOSURE

Use of 2-morpholino-4-amino-6-substituted-s-triazines for inducing depressant effects in animals.

This application is a continuation-in-part of copending applications Ser. Nos. 498,099 and 498,118, both filed Oct. 19, 1965 and both now abandoned.

BACKGROUND OF THE INVENTION

This invention relates to a method of inducing depressant effects in animals using certain s-triazines. More particularly it relates to the use of certain s-triazines as analgesics, muscle relaxants, anticonvulsants and tranquilizers and to pharmaceutical and veterinary compositions containing such triazines.

A considerable number of naturally occurring alkaloids and synthetic chemicals are available as useful analgesics, anticonvulsants and muscle relaxants. Repeated administration of many such analgesics creates the potential danger of drug addiction. The need for effective analgesics which minimize the hazards of drug addiction has long been recognized.

SUMMARY OF THE INVENTION

It is an object of the present invention to provide a novel method for inducing depressant effects in mammals. These depressant effects include sedative, analgesic, muscle relaxant, anticonvulsant and tranquilizing effects. Another object of the invention is to provide a novel method of pain control with minimum hazard of drug addiction. Yet another object is to provide a novel method for inducing depressant effects in mammals with certain 2-morpholino-4 - amino-6-substituted-s-triazines. The provisions for supplying the art with novel pharmaceutical and veterinary compositions capable of inducing neurological depressant effects in mammals forms another object.

These and other objects are accomplished by administering to a mammal an effective dosage of a 2-morpholino-4-amino-6-substituted-s-triazine of the formula

(1)

wherein

Y is $-\text{NRR}_1$ in which R is hydrogen or alkyl of 1-3 carbon atoms and R_1 is alkyl of 1-4 carbon atoms, phenyl or chlorophenyl; and R and R_1 together with the nitrogen atom can represent piperidino or lower alkyl-substituted piperidino; and

Z is

2

in which R_2 is hydrogen, alkyl of 1-3 carbon atoms,

where alkyl is of 1-3 carbon atoms and m is 0-3, or $-\text{alkylene}-\text{CN}$ where alkylene is of 2-4 carbon atoms;

$-\text{Cl}$;

where alkylene is of 1-3 carbon atoms;

where R_3 is $-\text{NH}_2$ or alkyl of 1-3 carbon atoms and alkylene is of 1-3 carbon atoms;

$-\text{CN}$;

$-\text{SCN}$;

$-\text{OR}_4$ where R_4 is alkyl of 1-3 carbon atoms;

where R_5 is hydrogen or alkyl of 1-3 carbon atoms;

$-\text{CSNH}_2$;

or

where R_6 is alkyl of 1-3 carbon atoms and alkylene is of 1-3 carbon atoms.

and salts thereof.

Representative species of the above s-triazines are:

- (1) 2-morpholino-4-ethylamino-6-piperazino-s-triazine
- (2) 2-morpholino-4-tert-butylamino-6-piperazino-s-triazine
- (3) 2-morpholino-4-dimethylamino-6-piperazino-s-triazine
- (4) 2-morpholino-4-anilino-6-piperazino-s-triazine
- (5) 2-morpholino-4-(2-chloroanilino)-6-piperazino-s-triazine
- (6) 2-morpholino-4-ethylamino-6-(4-methylpiperazino)-s-triazine hydrochloride
- (7) 2-morpholino-4-ethylamino-6-(4-(ethoxycarbonyl)piperazino)-s-triazine
- (8) 2-morpholino-4-ethylamino-6-(4-(ethoxycarbonylmethyl)piperazino)-s-triazine
- (9) 2-morpholino-4-(2,6-dimethylpiperidino)-6-(4-(2-cyanoethyl)piperazino)-s-triazine
- (10) 2-morpholino-4-(2-chloroanilino)-6-(4-(2-cyanoethyl)piperazino)-s-triazine
- (11) 2-morpholino-4-ethylamino-6-chloro-s-triazine
- (12) 2-morpholino-4-methylamino-6-chloro-s-triazine
- (13) 2-morpholino-4-diethylamino-6-chloro-s-triazine
- (14) 2-morpholino-4-dimethylamino-6-chloro-s-triazine
- (15) 2-morpholino-4-propylamino-6-chloro-s-triazine
- (16) 2-morpholino-4-isopropylamino-6-(2-morpholinoethyl)-thio-s-triazine
- (17) 2-morpholino-4-anilino-6-ureidomethyl-s-triazine
- (18) 2-morpholino-4-diethylamino-6-acetamidomethyl-s-triazine
- (19) 2-morpholino-4-tert-butylamino-6-acetamido-methyl-s-triazine
- (20) 2-morpholino-4-methylamino-6-cyano-s-triazine
- (21) 2-morpholino-4-diethylamino-6-cyano-s-triazine

- (22) 2-morpholino-4-diethylamino-6-thiocyanato-s-triazine
- (23) 2-morpholino-4-methylamino-6-methoxy-s-triazine
- (24) 2-morpholino-4-ethylamino-6-methoxy-s-triazine
- (25) 2-morpholino-4-dimethylamino-6-methoxy-s-triazine
- (26) 2-morpholino-4-diethylamino-6-methoxy-s-triazine
- (27) 2-morpholino-4-isopropylamino-6-(1-amino-1-(hydroxyimino) methyl)-s-triazine
- (28) 2-morpholino-4-ethylamino-6-(1-amino-1-(ethoxyimino) methyl)-s-triazine
- (29) 2-morpholino-4-isopropylamino-6-(1-amino-1-ethoxyimino) methyl)-s-triazine
- (30) 2-morpholino-4-tert-butylamino-6-(1-amino-1-(ethoxyimino) methyl)-s-triazine
- (31) 2-morpholino-4-dimethylamino-6-piperidino-s-triazine
- (32) 2-morpholino-4-ethylamino-6-thiocarbamoyl-s-triazine
- (33) 2-morpholino-4-ethylamino-6-benzylideneiminoxy-s-triazine
- (34) 2-morpholino-4-ethylamino-6-(N-2-hydroxyethyl-N-methylamino)-s-triazine

Compositions according to the present invention also comprise a pharmaceutical carrier which may either be solid material or a liquid. Preparations for oral administration can be liquids or solids or any combination of these forms, such as syrups, elixirs, powders, capsules, or tablets. Preparations for administration of the active agent in unit dose form can be powders, compressed tablets, or a powder enclosed in a suitable capsule of absorbable material such as gelatin. The powders or compressed tablets may also comprise suitable excipients and/or diluents such as starch, lactose, stearic acid, magnesium stearate, dextrin or polyvinylpyrrolidone.

Preparations for topical application may be in the form of a liquid, a powder, a salve, or as an aerosol.

Preparations for parenteral administration may be sterile solutions or suspensions in liquids such as water, physiological saline, benzyl alcohol, ethyl oleate, methylcellulose, dimethyl sulfoxide or other liquid excipients known in the pharmaceutical and veterinary formulation art.

Any of the above preparations may contain the triazines of the invention or may contain in addition other pharmaceutically active agents. For example, for topical application it may be desirable to include a germicide and/or a fungicide.

The unit dosage or therapeutically effective quantity of the triazines used according to this invention as analgesics, muscle relaxants, anticonvulsants and/or tranquilizers can vary over wide limits. For oral or parenteral administration in some cases, as little as 0.01 milligram of the active material per kilogram of body weight can be effective in the reduction of pain or in effecting sedation and muscle relaxation, while seldom will a dosage in excess of about 500 milligrams per kilogram of body weight be required. In general, for oral administration, the effective dosage will be from about 1.0 to 200 milligrams per kilogram of body weight, while for parenteral administration, the effective dosage will be from about 0.10 to about 100 milligrams per kilograms of body weight. Each dosage unit form—each capsule, tablet, ampoule, or prescribed dose—can contain from about 1 percent to about 95 percent of active material, based upon the total weight of the formulation and preferably contains from about 2.5 percent to about 50 percent of the active material, on the same basis. Of course, it is possible to administer the therapeutics without the use of a pharmaceutical carrier.

The therapeutic agents used according to the invention can be administered either prior to or after the onset of the condition to be treated, such as when they are used as: analgesics for the amelioration of pain; motor depres-

sants or tranquilizers to relieve nervous tension; central depressants to reduce hyperexcitability and induce sedation; or as muscle relaxants for relief from pain and discomfort of disorders involving muscle spasms.

PREPARATION

The s-triazines of this invention may be prepared by any of the conventional methods known in the art for preparing these types of s-triazines. The following descriptions are illustrative of some of the methods that may be used.

The starting material for the s-triazines disclosed herein is cyanuric chloride. From this s-triazine the various compounds of the invention may be prepared by replacement of the chloro groups with the various substituents depicted in Formula I.

Thus, the amino substituents, i.e., morpholino, —NRR, piperazino and N-alkyl piperazino and

may be readily introduced by the known reactions of replacing the chloro substituents of chloro-s-triazines by reaction with the respective amines as described in Elderfield, R. C. *Heterocyclic Compounds* N.Y., J. Wiley and Sons, Inc. 1961, pp. 669-671.

The cyanoalkylpiperazino-s-triazine are readily prepared by reaction of a piperazino-s-triazine with a cyanoalkene at moderate temperatures in a lower alkanol solvent in the presence of a catalytic amount of benzyltrimethylammonium hydroxide.

The N-alkoxycarbonylpiperazino-s-triazines may be prepared by reacting a piperazino-s-triazine with an alkyl chloroformate ($\text{Cl}-\text{C}(\text{O})\text{O}-\text{alkyl}$) in a halogenated hydrocarbon solvent in the presence of triethylamine. The remaining N-substituted piperazino-s-triazines, those substituted by an alkoxycarbonylalkyl group, may be prepared by reacting a piperazino-s-triazine with an appropriate alkyl ester of a chloroalkanoic acid in an organic solvent such as an ether at moderate temperatures.

The morpholinoalkylthio groups may be introduced by reacting a mercapto-s-triazine with a N-chloroalkylmorpholine hydrochloride in an aqueous solution of sodium hydroxide.

The ureidoalkyl substituents (R_3 is $-\text{NH}_2$) may conveniently be introduced by reaction of an appropriate aminoalkyl-s-triazine with potassium cyanate using water for the reaction media. The alkylcarbonylaminoalkyl substituents (R_3 is alkyl) may be prepared by hydrogenating a cyano or cyanoalkyl-s-triazine in the presence of the appropriate alkanoic acid anhydride.

The cyano substituents can be introduced by the methods described in U.S. 3,234,225 while the $-\text{SCN}$ group may be introduced by the methods described in U.S. 3,120,468.

The alkoxy substituents may also be introduced by methods known in the art, e.g., by refluxing a chloro-s-triazine in a reaction media of a lower alkanol and acetone with a solution of sodium in a lower alkanol.

The $-\text{C}(\text{NH}_2)=\text{NOR}_2$ group may be introduced (R_2 is hydrogen) by refluxing a cyano-s-triazine with hydroxylamine hydrochloride in a lower alkanol diluent in the presence of an aqueous solution of sodium hydroxide. The $-\text{C}(\text{NH}_2)=\text{NO-alkyl}$ substituents may be prepared by heating a mixture of a cyano-s-triazine and an O-alkylhydroxylamine (H_2NOR where R is alkyl) in a lower alkanol solvent in the presence of hydrogen sulfide.

The thiocarbamoyl group ($-\text{CSNH}_2$) may be introduced by heating a mixture of a cyano-s-triazine, triethylamine and hydrogen sulfide in an ether diluent.

The benzylideneiminoxy substituent may be introduced by reacting a chloro-s-triazine with benzaldoxime in an organic diluent in the presence of a base such as triethylamine.

The salts of the s-triazines of the invention are prepared by the conventional method of reacting the s-triazine with

an inorganic or organic acid. Examples of such acids are sulfuric, phosphoric, hydrochloric, sulfamic, benzylsulfonic, maleic, fumaric, succinic, tartaric and the like. The salt-forming acid should be that is physiologically acceptable for administration to mammals. The hydrochloride salts are preferred.

The following examples illustrate some of the methods for preparing the s-triazines of the invention.

Example I

24 g. (0.1 mol) 2-ethylamino-4-chloro-6-morpholino-s-triazine and 25.8 g. (0.3 mol) piperazine, mixed in 100 ml. ethanol, were refluxed for 30 minutes. After distilling off the ethanol, the residue was taken up in methylene chloride and washed with water. After distilling off the methylene chloride, stirring the residue in ether, 22.5 g. 2-ethylamino-4-piperazino-6-morpholino-s-triazine, M.P. 110-112° C., crystallized out.

Example II

24.35 g. (0.1 mol) 2-chloro-4-morpholino-6-ethylamino-s-triazine was dissolved in a mixture of 150 ml. acetone and 50 ml. methanol and heated while a solution of 2.3 g. (0.1 mol) sodium in 50 ml. methanol was slowly added. The mixture was refluxed for 1 hour. After cooling, the salt was filtered out and the solution concentrated. The concentrate was taken up in methylene chloride and washed with water. After drying, the solvent was removed, leaving 19.4 g. 2-methoxy-4-morpholino-6-ethylamino-s-triazine, M.P. 127-132° C.

Example III

(a) To 18.45 g. (0.1 mol) cyanuric chloride, dissolved in 200 ml. methylene chloride, was slowly added with stirring at 0° C., 22.6 g. (0.2 mol) of 2,6-dimethylpiperidine. After removing the precipitated dimethylpiperidine hydrochloride, 17.4 g. (0.2 mol) morpholine was added to the stirred solution at a temperature of 20° C. After 2 hours, the precipitated morpholine hydrochloride was filtered off, the solution washed with water, dried and concentrated. After washing the concentrate with ether and then drying, 21.2 g. 2-morpholino-4-chloro-6-(2,6-dimethylpiperidino)-s-triazine, M.P. 168-75° C., was obtained.

(b) 31.15 g. (0.1 mol) of the product of 3(a) was gradually added to a boiling solution of 58.2 g. (0.3 mol) piperazine hexahydrate in 200 ml. ethanol and refluxed for 30 minutes. After cooling, the solution was filtered and concentrated. After the crystalline residue from the concentrate was washed with water and dried, there was obtained 27.5 g. 2-morpholino-4-piperazino-6-(2,6-dimethylpiperidino)-s-triazine, M.P. 146-48° C.

Example IV

24.4 g. (0.1 mol) 2-morpholino-4-chloro-6-ethylamino-

s-triazine was refluxed for 1 hour with 20 g. (0.2 mol) N-methylpiperazine in 200 ml. ethanol. After concentrating the solution, the concentrate was taken up with 200 ml. methylene chloride and washed with water. After drying and concentrating the solution, the sirupy residue was dissolved in ether and filtered. After introducing HCl gas into the sirupy residue, 25 g. of the hydrochloride of 2-morpholino-4-(N-methylpiperazino)-6-ethylamino-s-triazine, M.P. 230-38° C., was obtained.

Example V

100 g. 2-diethylamino-4-morpholino-6-cyano-s-triazine was added to 450 ml. acetic anhydride and hydrogenated on a Raney-Nickel catalyst at 60° C. with hydrogen. The solution was evaporated to dryness, taken up with water and the pH adjusted to 9 with soda. The residue was filtered and the product, 2-diethylamino-4-morpholino-6-acetamidomethyl-s-triazine, M.P. 88-90° C., was crystallized from isopropanol.

PREFERRED EMBODIMENTS

While the s-triazines of Formula I show some depressant effects in mammals, there are differences both quantitative and qualitative exhibited by individual members of the class. Especially preferred depressants because of their activity as analgesics, muscle relaxants, anticonvulsants, and/or tranquilizers are the s-triazine of the formula.

35 wherein R is alkyl of 1-4 carbon atoms, preferably ethyl, and R₁ is hydrogen or alkyl of 1-3 carbon atoms, preferably hydrogen; and Z is alkoxy of 1-2 carbon atoms, preferably methoxy, or piperazino; and salts thereof. Preferred s-triazines within this subclass are:

2-morpholino-4-ethylamino-6-piperazino-s-triazine
2-morpholino-4-tert-butylamino-6-piperazino-s-triazine
2-morpholino-4-dimethylamino-6-piperazino-s-triazine
2-morpholino-4-methylamino-6-methoxy-s-triazine
2-morpholino-4-ethylamino-6-methoxy-s-triazine
2-morpholino-4-dimethylamino-6-methoxy-s-triazine
2-morpholino-4-diethylamino-6-methoxy-s-triazine

45 The following examples are presented to illustrate certain pharmacological responses induced by triazine compositions of the invention. These examples should in no way be regarded as limiting the scope of the invention.

50 The results of the various pharmacological responses tested are shown in Table I.

¹ Numbers correspond to numbered triazines in columns 2 and 3.

Analgesic response (a).—The presence of an analgesic effect was identified as an absence of a struggling or phonating response to a manual pinch of the tail of treated mice. The laboratory white mice for each treatment were placed in individual compartments. The mice were orally intubated with the test compound at the dosage of 500 milligrams per kilogram, and 15 minutes, 1 hour, 2 hours, 4 hours and 24 hours after treatment a pinch of the tail was applied to each mouse. Any compound inducing an analgesic response in 50 percent of the mice at any of these test intervals was considered active in this test. Some of the compounds were tested at lower dosages.

While the exact safety factor has not been evaluated for all compounds of the invention, it has been found that the effective analgesic dose of the triazines of the invention is considerably lower than the toxic dose (LD₅₀).

Muscle relaxant response (b).—As in (a) above, mice were orally intubated with the test compound and the muscle relaxant effects of the compounds were evaluated. The procedure for assessing skeletal muscle relaxant activity involves an evaluation of passivity, flaccidity and pinnal reflex blockage. Passivity is defined as an absence of the struggle behavior of the animal when manipulated manually and may indicate skeletal muscle relaxation, central depression, tranquilization, paralysis, or anesthesia. Flaccidity is measured by the decreased tonus of skeletal musculature and may indicate myorelaxant activity, central depression, or paralysis. The pinnal reflex is tested by touching the inner aspects of the ear with a fine wire to elicit a characteristic ear twitch. An impairment of this reflex suggests an inhibition of polysynaptic reflexes.

Analgesic response—intraperitoneal (c).—The analgesic response was determined in laboratory white mice by injection of the triazines under test at an intraperitoneal dosage of 100 ml. per kg. The results were obtained by evaluation similar to that described for the Approximate Analgesic Dose—Oral. The compounds were rated on a one plus (+) to four plus (++++) scale. When 1-2 mice out of ten showed an analgesic response, a + rating was assigned; ++ indicated that 3-6 out of ten mice responded; +++ indicated that 7-9 out of ten responded; while a ++++ rating meant that all ten mice gave an analgesic response at the dosage tested.

Muscle relaxant—tranquilization response (d).—The muscle relaxant effects, as expressed by passivity, flaccidity and pinnal reflex blockage, were assessed in laboratory mice injected intraperitoneally with 100 mg./kg. of the test compound as in (b). In addition the tranquilizing effects of the compounds under test were evaluated by the pernicious preening test (Wilfond, J. G., et al., Fed. Proc. 19:20, 1960). The pernicious preening behavior was elicited by painting the rear of the mice with a pilocochesive dye. A violent unremitting tearing of the stiff cohering strands of hair constitutes the pernicious preening behavior. Thirty minutes after injection, the pilocochesive

25 dye was applied and the presence or absence of the compulsive behavior was noted for a 10 minute interval. The ratings for the muscle relaxant response are based upon the scale given in (c). Effective antagonism of pernicious preening is shown with the same scale as in (c). That is, + = 1-2 mice out of ten, ++ = 3-6 mice out of ten, +++ = 7-9 mice out of ten and ++++ = 10 mice out of ten responded. Some of these values for the individual triazines were determined at a dosage of 32 mg./kg. while the others were determined on the basis of ED₅₀ values, the dose at which 50 percent of the treated animals exhibit an effective response. These ED₅₀ values were then translated into the +1 to +4 scale by the following criteria: ED₅₀ values of 30-100 mg./kg. = +, 10-30 mg./kg. = ++, 3-10 mg./kg. = +++ and <3 mg./kg. = +++++.

40 45 50 55 60 65 70 75 80 85 90 95 Anticonvulsant response (e).—The test procedures used were maximal electroshock and antstrychnine assay methods. The test compound was intraperitoneally injected into laboratory mice and after 30 minutes the anticonvulsant activity was measured. The technique employed in the maximal electroshock method was essentially that of Swinyard, E. A., J. Amer. Pharm. Assoc. 38:201 (1949). The mice were subjected to an alternating current stimulus, about equal to three times the current necessary to produce maximal seizures, and prevention of the hindlimb tonic extensor phase was considered to be an effective anticonvulsant action. In the antstrychnine assay, the mice were intraperitoneally injected with the test compound and then were challenged with a lethal intraperitoneal dose of strychnine sulfate. Increase in survival time against the lethal action of strychnine of greater than three standard deviations of the control mean was considered an effective action. Anticonvulsant activity in these tests suggests skeletal muscle relaxation or efficacy against epileptic seizures. Effective antagonism of maximal electroshock seizure and antstrychnine activity are given on the same +1 to +4 scale as in (c). Some of these values for the individual triazines in the maximal electroshock seizure test were determined at a dosage of 100 mg./kg. while the others were determined on the basis of ED₅₀ values, the dose at which 50 percent of the treated animals exhibited an effective response. These ED₅₀ values were then translated into the +1 to +4 scale by the following criteria: ED₅₀ values of 100-300 mg./kg. = +, 30-100 mg./kg. = ++, 10-30 mg./kg. = +++ and <10 mg./kg. = +++++. The antstrychnine activities for the individual triazines were also determined in either of two ways. Some are based on the response ratio at 180 mg./kg. while the others on the ED₅₀ values. The criteria for translating the ED₅₀ values to the +1 to +4 scale is the same as for the maximal electroshock seizure test.

We claim as our invention:

1. A depressant veterinary and pharmaceutical composition comprising
(a) a compound of the formula

wherein

Y is $-\text{NRR}_1$ in which R is hydrogen or alkyl of 1-3 carbon atoms and R_1 is alkyl of 1-4 carbon atoms, phenyl or chlorophenyl; and R and R_1 together with the nitrogen atom can represent piperidino or lower alkyl-substituted piperidino; and

Z is

in which R_2 is hydrogen, alkyl of 1-3 carbon atoms,

where alkyl is of 1-3 carbon atoms and m is 0-3, or —alkylene—CN where alkylene is of 2-4 carbon atoms;

Cl;

where alkylene is of 1-3 carbon atoms; 40

where R_3 is $-\text{NH}_2$ or alkyl of 1-3 carbon atoms and alkylene is of 1-3 carbon atoms; 45
 $-\text{CN}$;
 $-\text{SCN}$;
 $-\text{OR}_4$ where R_4 is alkyl of 1-3 carbon atoms;

where R_5 is hydrogen or alkyl of 1-3 carbon atoms; 55

$-\text{CSNH}_2$;

or

where R_6 is alkyl of 1-3 carbon atoms and alkylene is of 1-3 carbon atoms; and salts thereof; and

(b) a physiologically acceptable carrier, the percent by weight of (a) in the total formulation being from about one to 95.

2. The veterinary and pharmaceutical composition of claim 1 wherein Y is $-\text{NRR}_1$ in which R is alkyl of 1-4 carbon atoms and R_1 is hydrogen or alkyl of 1-3 carbon atoms and Z is alkoxy of 1-2 carbon atoms or piperazino.

3. The veterinary and pharmaceutical composition of claim 2 wherein R is ethyl and R_1 is hydrogen.

4. The veterinary and pharmaceutical composition of claim 3 wherein Z is methoxy.

5. The veterinary and pharmaceutical composition of claim 3 wherein Z is piperazino.

6. A method of inducing a depressant response in mammals comprising administering to said mammal in need thereof an effective dosage of a compound of the formula

wherein

Y is $-\text{NRR}_1$ in which R is hydrogen or alkyl of 1-3 carbon atoms and R_1 is alkyl of 1-4 carbon atoms, phenyl or chlorophenyl; and R and R_1 together with the nitrogen atom can represent piperidino or lower alkyl-substituted piperidino; and

Z is

in which R_2 is hydrogen, alkyl of 1-3 carbon atoms,

where alkyl is of 1-3 carbon atoms and m is 0-3, or —alkylene—CN where alkylene is of 2-4 carbon atoms;

Cl;

where alkylene is of 1-3 carbon atoms;

where R_3 is $-\text{NH}_2$ or alkyl of 1-3 carbon atoms and alkylene is of 1-3 carbon atoms;

$-\text{CN}$;

$-\text{SCN}$;

$-\text{OR}_4$ where R_4 is alkyl of 1-3 carbon atoms;

where R_5 is hydrogen or alkyl of 1-3 carbon atoms;

$-\text{CSNH}_2$;

or

where R_6 is alkyl of 1-3 carbon atoms and alkylene is of 1-3 carbon atoms; and salts thereof.

7. The method of claim 5 wherein said compound is administered orally to said mammal.

8. The method of claim 6 wherein said compound is administered parenterally to said mammal.

9. The method of claim 6 wherein Y is $-\text{NRR}_1$ in which R is alkyl of 1-4 carbon atoms and R_1 is hydrogen

11

or alkyl of 1-3 carbon atoms and Z is alkoxy of 1-2 carbon atoms or piperazino.

10. The method of claim 9 wherein R is ethyl and R₁ is hydrogen.

11. The method of claim 10 wherein Z is methoxy.

12. The method of claim 10 wherein Z is piperazino.
